LOOSE LEAF BOOK CONSTRUCTION

Filed Feb. 4, 1944

UNITED STATES PATENT OFFICE

2,435,521

LOOSE-LEAF BOOK CONSTRUCTION

Murray Vernon, New York, N. Y., assignor to
 S. E. & M. Vernon Inc., New York, N. Y., a corporation of New York

Application February 4, 1944, Serial No. 521,015

2 Claims. (Cl. 129—24)

1

This invention relates generally to loose leaf binders and more particularly to loose leaf binder construction, which while possessing the desired properties of permitting pages to be inserted, withdrawn or changed in position, is easily and economically fabricated of non-critical materials.

Among the principal objects of the present invention lies the provision of loose leaf notebook construction in which known independent binder rings are combined with other elements to provide a unitary book in which the rings are independently operable.

Another object herein lies in the provision of structure of the class described in which the rings may be independently operated by a simple manual motion either to an "open" position (when sheets may be inserted or withdrawn), or to a "closed" position in which, barring rupture of the sheets themselves, the sheets are securely retained in position in the book.

A still further object of the present invention lies in the provision of a loose leaf notebook of the ring binder type of construction in which a kind of "snap" action is obtained without the use of springs as such but by the action of the binder rings.

A feature of the invention lies in the simple low cost manufacture thereof so that the same may have a consequent wide sale and distribution.

A further feature of the present invention lies in the fact that the support element protects the rings from undue distortion so as to extend the useful life thereof.

A further feature of the present invention lies in the fact that the support element and rings form a basic unit so that the cover of the notebook may be composed of any desired material.

These objects and other incidental ends and advantages will more fully appear in the progress of this disclosure and be pointed out in the appended claims.

In the drawing similar reference characters designate corresponding parts throughout the several views:

Figure 1 is a fragmentary rear elevational view, partly in section, of an embodiment of the invention.

Figure 2 is a fragmentary enlarged sectional view as seen from the plane 2 on Figure 6.

Figure 3 is a fragmentary sectional view partly in elevation as seen from the plane 3—3 on Figure 2.

2

Figure 4 is a sectional view partly in elevation as seen from the plane 4—4 on Figure 2.

Figure 5 is a view corresponding to Figure 4, but showing the binder ring thereat in an open position.

Figure 6 is a perspective view of a loose leaf binder embodying the invention in closed position.

In accordance with the invention, as illustrated in Figures 1-6, inclusive, the device generally indicated by numeral 20 includes a front cover 21, a rear cover 22, a rear member or saddle 23, a support element 24 and rings 25.

The covers 21 and 22 and the rear member or saddle 23 may be of any suitable construction well known in the art, such as stiff cardboard covered with cloth, artificial leather, and so forth. The covers 21 and 22 are thus hingedly connected to the rear member 23 along the hinged portions 27 and 28. While the illustration in the drawings of an embodiment of the invention, the device is illustrated as having three rings, it will be obvious to those skilled in the art to which the present invention relates that any desired number of rings may be used in any desired inter-spacing.

The rear member 23 is preferably slightly curved to produce a convex outer surface 29 and a concave or forward surface 30. The degree of concavity of the surface 30 preferably substantially conforms to the convexity of the rear or inner surface 31 of the support element 24. The support element 24 is preferably fabricated of any suitable material such as a strip of hard wood and the front or normally exposed surface thereof indicated by numeral 32 is preferably of convex configuration. The support element 24 is preferably not as long as the rear member 23.

The support element 24 is provided with a plurality of channels 33, as many channels as there are rings. The channels are of uniform construction which is best seen in Figures 1-5, inclusive.

By reason of the fact that the channels 33 are of uniform construction, a detailed description of one will suffice for all. A channel 33 has side walls 34 and 35 and a curved or arcuate top wall 36, the side walls 34 and 35, of the channel 33, supporting the ring in a substantially upright position, that is to say perpendicularly of the surface 32 of the support element 24. The channels 33 are closed at the rear thereof by the forward surface of the rear member or saddle 23, particularly at the portions 37, 38 and 19. The

portion 19 supports the ring underneath or rearwardly of the same when the ring is in a closed position thereof, while the portions 37 and 38 support the ring when the ring is in an open position thereof. The support element 24 is further provided with a longitudinally arranged channel 39 which is disposed in the rear or inner surface 31 at the central portion thereof. The channel 39 intersects the channels 33 and terminates at 50 slightly inwardly of the ends 52 and 53. The channel 39 serves therefore, to enlarge the central portions of the channel 33 at the portions 19. This enlargement is adapted to accommodate a corresponding enlargement of the rings 25 thereat.

The rings 25 are substantially identical and therefore, a description of one will suffice for all. A ring 25 includes a sheet carrying portion 42 and a retainer portion 43. The ring 25 is preferably of uniform curvature alignment along the circumference of a true circle, when the ring is in a closed position thereof. For the purposes of this description, the sheet carrying portion is generally considered as that visible in Figure 2 while the retainer portion is that disposed within the confines of the support element in Figure 4. Thus, the ends of the sheet carrying portion 42 run into the adjoining ends of the retainer portion. The sheet carrying portion is preferably split in a zig-zag manner at the central part thereof to form the ring terminals 46 and 47. The retainer portion includes two separate ends 44 and 45 which are hingedly connected in lapped relationship by the pin 41. The heads of the pin 41 form enlargements in the retainer portion 43 of the ring 25.

The ring itself is preferably composed of a material having the quality of resiliency, as for example, steel or plastic such as cellulose acetate. Obviously the ring may be composed of other materials, such as die-cast metals, or thermoplastic or thermosetting plastics, well known. The ring may be molded in the shape shown or it may form up under heat and/or pressure in suitable dies and/or jigs.

Since the rings are composed of resilient material, the terminals 46 and 47 may be temporarily laterally separated sufficiently so that the projections 58 and 59 may disengage the corresponding depressions in the opposite parts of the sheet carrying portion thereof and then the two halves of the ring 60 and 61 may be pivotally moved and separated providing a passage 63 through which suitably orificed sheets, not shown, but well known in the art may be inserted. When so positioned, the sheet may be hooked upon and penetrated by either of the terminals 46 or 47. The rings may be closed by moving them toward each other; the diagonally arranged surface at the tips of the terminals acting in a wedge and ratchet manner.

The device may be assembled by placing one of the rings 25 in each of the channels 33 with the pins 41 engaging the channel 39. Then, the concave surface 30 of the rear member 23 is placed against the rear or inner surface 31 of the support element 24 and they are fixedly secured together by any suitable means, such as for example, the rivets 55 which engage suitably aligned orifices 56 and 57 in the support element 24 and the rear member 23, respectively.

Thus, the device may be operated in one manner as follows. Assuming all of the rings 25 to be in the closed position thereof as shown in Figure 2, said rings may be grasped consecutively

and the terminals 46 and 47 on each of the rings separated by laterally shifting the projections 58 and 59 out of line and separating the halves 60 and 61 of the rings 25. The opening movement 5 of the halves 60 and 61 away from each other will be restricted by the engagement of the portions of the rings adjacent the ends with the portions 37 and 38 of the rear member 23. The perforated sheets (not shown) may now be placed upon or removed from either of the sheet carrying portions of the halves of the rings. After the sheets have been placed or removed, the ring halves may be moved to the closed position thereof either by independently and consecutively manually grasping the rings and rotating them toward each other about the pins 41 or by grasping the covers 21 and 22, the inner opposed surfaces of which at 10 and 71 engage the ring halves to draw said covers toward each other. This will simultaneously cause all of the rings to close by the wedge and snap action of the interengaging projections and depressions on the terminals 46 and 47.

It may thus be seen that the rings 25 are prevented from rotating annularly by the projections on the ends of the pins 41 engaging with the channel 39, thus the opening terminals 46 and 47 on each of the rings are maintained in an aligned and predetermined spatial interrelationship.

It may thus be seen that I have provided a novel and useful loose leaf notebook binder construction which is efficient in use and economical in manufacture.

I wish it to be understood that I do not desire to be limited to the exact details of construction shown and described, for obvious modifications will occur to a person skilled in the art.

I claim:

40. 1. A sheet retaining book for detachably holding perforated sheets, the book comprising a front cover, a rear cover and a saddle, all of fibrous covered material, a member having a rear face shaped to give said saddle the configurations 45 of the back of a bound book, a plurality of sheet holding rings, each ring comprising two portions joined by a hinge, said hinge projecting beyond the sides of said ring, channels in said member, one for each ring, each channel having a top wall of substantially the same configuration as the closed ring, an intersecting channel in said member located substantially in the longitudinal center of said saddle, each ring having the hinge accommodated in said intersecting channel, and fastening means for securing the member to the saddle.

2. A sheet retaining book for detachably holding perforated sheets, comprising a mounting for the paper holding means of the book, said mounting consisting of a single piece of solid material having a curved rear face, said paper holding means comprising a plurality of sheet holding rings, each ring comprising two portions joined by a hinged connection, each hinged connection projecting beyond the sides of the ring, means for each ring to latch it in sheet retaining position, the solid material of said mounting having ring-receiving transverse channels, each channel conforming in depth to the contour of the inner periphery of the closed ring, a saddle secured to said mounting on its curved face, front and rear covers for said book flexibly connected to said saddle, each ring being kept in sheet receiving and retaining positions by the saddle and said trans-

verse grooves, said solid material of said mounting having groove means to accommodate the projection of the hinged connection of each ring, the inner contour of the channels and the saddle setting the limit of movement of the rings from closed sheet retaining position to the open sheet receiving position.

MURRAY VERNON.
